UNITED STATES PATENT OFFICE.

ABRAHAM P. RINDSKOPF, OF NEW YORK, N. Y.

DESIGN FOR A SWIMMING-BAG.

41,797.

Specification for Design.

Patented Sept. 19, 1911.

Application filed April 19, 1910. Serial No. 556,454. Term of patent 7 years.

To all whom it may concern:

Be it known that I, ABRAHAM P. RINDSKOPF, a citizen of the United States, residing in the city of New York, borough of Brooklyn, in the county of Kings and State of New York, have invented a new, original, and ornamental Design for a Swimming-Bag, of which the following is a specification, reference being had to the accompanying drawing, forming part thereof.

The figure is a plan view of the swimming bag, showing my new design.

I claim:

The ornamental design for a swimming bag, as shown.

ABRAHAM P. RINDSKOPF.

Witnesses:

WALTON HARRISON,
PHILIP D. ROLLHAUS.
